ATTORNEY.

UNITED STATES PATENT OFFICE.

PATRICK MAGINNIS, OF KIMBALL, NEBRASKA.

EXTENSIBLE TROUGH.

SPECIFICATION forming part of Letters Patent No. 700,522, dated May 20, 1902.

Application filed August 5, 1901. Serial No. 70,956. (No model.)

To all whom it may concern:

Be it known that I, PATRICK MAGINNIS, residing at Kimball, in the county of Kimball and State of Nebraska, have invented certain useful Improvements in Extensible Troughs; and I do hereby declare that the following is a full, clear, and exact description of the invention, such as will enable others skilled in the art to which it appertains to make and use the same, reference being had to the accompanying drawings, which form a part of this specification.

This invention relates to a new and novel improvement in extensible troughs.

15 The object of my invention is to provide a trough adapted to be made the length of one unit or extended to comprise the combination of a plurality of units to form a trough which may be readily taken apart and nested 20 one unit upon the other, so that the same may be readily nested, crated, and shipped.

In the accompanying drawings I have shown in Figure 1 a side elevation of a trough embodying my invention comprising two 25 units, with portions removed to disclose the structure. Fig. 2 shows a top view of the clamping-bar I use, while Fig. 3 shows a cross-sectional view disclosing the arrangement of the parts at the union of two elements or 30 units.

My invention comprises a trough - shell, preferably made of sheet metal, and which is nothing more or less than a rectangular piece of sheet metal which has its upper ends 35 flared outward, as is shown at *b*, to form a broad edge on top and at the same time give stability to the structure when assembled. These trough shells or sections are preferably identical in length, and in Fig. 1 two 40 such counterpart trough shells or sections *A* and *B* have been shown. Each shell is provided near each end with an inwardly-extending rib, which upon the opposite side forms a groove into which the corresponding 45 or complementary rib of the adjoining section fits, as is disclosed in Fig. 1. The trough-sections which are placed at the ends are closed and reinforced by means of the end panels *D*, preferably of wood, which panels 50 are grooved, as is shown at *c*, so as to receive the web *a* of the end trough-sections. These end sections *D*, which, as has been stated,

are preferably made of wood, are next provided with an iron bar *2* above, through which extend the **U**-shaped loop-bars *C*, having the ends threaded to receive the nuts *3*, so that at the ends each trough-section is clamped and adjustably secured to an end panel *D* by means of these **U**-shaped loop-bars, which are secured by means of the nuts 55 *3*. The grooves *a* within the trough sections or shells form seatings within which the **U**-shaped loop-bars are held, as is clearly shown in Fig. 1, so that these bars cannot be displaced. 60

In securing two units or trough-sections, as *A* and *B*, in order to form an endless trough I unite the ends of the trough-sections in placing the ribs one upon the other, but interposing between them a packing-strip *8*, as is 65 shown in Fig. 1, and then placing upon the top or inner trough-section a semicircular ribbed strip *K*, which strip *K* extends beyond the upper edge of the trough-section *B*, as is shown in Figs. 1 and 3. By virtue of the 70 groove within this semicircular rim *K* this rim is not likely to be laterally displaced.

Transversely spanning the trough wherever two trough-sections are united is a spanner-bar *6*, provided with the downwardly-extending ears *7*, which are adapted to snugly work 75 against the upper rim portions *K* to force them against the sides of the innermost trough-section, as is clearly shown in Fig. 3. This spanner-bar *6* has its ends perforated, 80 as is shown at *5* in Fig. 2, and through these perforations pass the threaded ends of the **U**-shaped loop-bar *C*, which above is provided with suitable nuts, as is shown in Fig. 3. 85

Now in order to join two trough-sections it 90 is simply necessary to screw down the nuts *3*, which operation carries the **U**-shaped loop-bar *C* inward against the adjacent trough-sections, while the spanner-bar *6* forces the rim *K* downward to tightly pinch and clamp 95 the two trough-sections *A* and *B* together, and this rim being made of sheet metal cannot buckle inward, but insures a snug contact between itself and the adjacent trough-shell, so insures the inner trough section or shell 100 being tightly pinched upon the interposed packing-strip *8* to form a water-tight union. By means of this structure I can form water-ing-troughs of any number of lengths, or these

semicircular trough-sections can be used for the purposes of a washtub or like implement, such as feed-troughs or the like. A plurality of these trough-sections united are nicely 5 adapted to form flumes. One of the end panels D may be provided with an opening x, as is shown in Fig. 3, into which a suitable plug may be driven, so that the trough may be emptied. When taken apart, they can be 10 easily nested, so that they may be shipped in a knockdown condition. It is of course understood that these trough-sections may be made of various lengths and thicknesses and that the end panels D, which I have de- 15 scribed as being made of wood, might also be made of iron or any other suitable material.

The device is noticeable because of its extreme simplicity, and,

Having thus described my said invention, 20 what I claim as new, and desire to secure by United States Letters Patent, is—

An extensible trough comprising a plurality of counterpart sheet-metal semicircular trough-sections, having their upper opposite 25 edges bent at right angles and being provided at each end with an inwardly-extending rib forming upon the outside a groove, in combination with two counterpart semicircular end panels provided with peripheral grooves 30 adapted to receive the inwardly-extending

ribs of aforementioned trough-sections, an upper strengthening-bar extending across and beyond each end panel, each bar being provided with end perforations, U-shape loop-bars seating within aforementioned grooves 35 exteriorly of each end trough-section, the upper ends of said loop-bars extending through said upper strengthening-bars and being secured by means of suitable nuts, a packing-strip interposed between the united ends of 40 said trough-sections where they join one another, a semicircular grooved strip disposed interiorly above each point of union between two trough-sections to receive the aforementioned inwardly-extending rib of the upper- 45 most trough-section, a transverse spanner-bar provided with downwardly-extending ears adapted to bear against said semicircular rib at the upper ends, said spanner being provided with extending perforated ends and a 50 U-shaped intermediate loop-bar within the groove of the outer trough-section, passing through the perforated ends of said spanner and being suitably secured in the manner set forth.

PATRICK MAGINNIS.

In presence of—

GEORGE W. SUES,

RAYMOND J. DAVENPORT.
